SIEVE SHAKING MACHINE

Gorden E. Bodien, Minneapolis, and Joseph R. Foster, St. Paul, Minn.

Application July 11, 1934, Serial No. 734,600

2 Claims. (Cl. 209—340)

Our invention relates to sieve shaking machines. It relates more particularly to that class of devices in which a column of sieves of successively increasing fineness from top to bottom has a shaking motion imparted thereto, whereby the material deposited in the upper sieve is separated by the successive sieves according to the size of the particles composing the material. A particular use to which the device is adapted is for testing the fineness of sand as determined by the ability thereof to pass through the different sieves. An object of the invention is to provide a machine of this character in which the sieves are subjected to a pendulum-like motion combined with a tapping or jarring action. Another object of the invention is to provide a machine of this character which is of simple and inexpensive construction and yet extremely efficient in operation.

The full objects and advantages of our invention will appear in connection with the following detailed description and the novel features embodied in our invention will be particularly pointed out in the claims.

In the accompanying drawings which illustrate a practical embodiment of our invention, Fig. 1 is a sectional elevational view, the section being on the line 1—1 of Fig. 5 and on an enlarged scale. Fig. 2 is a detail view showing the operation of a crank pin. Fig. 3 is a similar view showing further the operation obtained by the crank pin. Fig. 4 is a front elevational view. Fig. 5 is a view in central vertical section. Fig. 6 is a view taken on the line 6—6 of Fig. 4.

Referring to the particular construction shown in the drawings, it will be seen that we provide a base member 10 containing a slot 12 and provided with ears 14 by means of which it may be bolted to any suitable support 16 such as a table or bench. Extending up from the base is a standard 18 having an outturned upper portion 20 which pivotally supports a pendulum device consisting of two rods 22 which diverge from the pivot as shown in Fig. 1 and then extend down parallel to each other, the divergent portions of the rods being connected by a brace rod 24. The rods 22 at their lower ends carry a circular plate 26 having a raised periphery within which is adapted to fit a pan 28 having a closed bottom. Superimposed upon the pan 28 when the device is in use is a series of sieves 30 having screens 32 for their bottom members, the screens increasing in fineness from the upper one to the lower one. A cross bar 34 is slidably mounted on the rods 22 and at its ends is provided with clamps 36 by means of which the cross bar may be clamped upon the uppermost one of the sieves 30. Extending down from the circular plate 26 are two spaced fingers 38 adapted to swing in the slot 12 and between which

is a crank pin 40 whose diameter is somewhat less than the distance between the fingers. The crank pin 40 is carried by a disk 42 secured to the inner end of a shaft 44 mounted in a bearing 46 carried by the base 10. The outer portion of the shaft 44 carries a balance wheel 47 and a pinion 48. This pinion meshes with a gear 50 secured to a stub shaft 52 adapted to be rotated by a hand crank 54 or in any other suitable manner.

The operation and advantages of our invention will be readily understood in connection with the foregoing description and the accompanying drawings. When the shaft 44 is rotated in the manner previously described, the crank pin 40 will impinge alternately upon the two fingers 38 and cause the rods 22 carrying the sieves 30 to swing like a pendulum, it being obvious that the lowermost sieve has the longest arc of oscillation. Due to the fact that the diameter of the crank pin 40 is less than the distance between the fingers 38, a tapping action will be imparted to the sieves at each oscillation. This action will be understood by referring to Figs. 2 and 3. Fig. 2 represents the extent of movement toward the left caused directly by the crank pin impinging on the left hand finger. However, the momentum of the pendulum carries it further so that the right hand finger strikes against the crank pin thereby imparting a knock to the sieves which action is duplicated when the pendulum is swung towards the right. This tapping or jarring action will be repeated as long as the device is continued in operation.

We claim:

1. A sieve shaking machine comprising a sieve column consisting of a series of screens increasing in fineness from the upper to the lower one, a fixed horizontal pivot upon which said column is suspended for pendulum-like movement thereof to and fro in a vertical plane only, two spaced fingers associated with the lower end of said column, a crank pin between said fingers for imparting said movement to said column and arranged to also give a jarring action to said column, and means for operating said crank pin.

2. A sieve shaking machine comprising a sieve column consisting of a series of screens increasing in fineness from the upper to the lower one, a fixed horizontal pivot upon which said column is suspended for pendulum-like movement thereof to and fro in a vertical plane only, two spaced fingers associated with the lower end of said column, a crank pin between said fingers having a diameter less than the distance between said fingers, a disk to which said crank pin is secured, a shaft to which said disk is secured, and means for rotating said shaft.
